Inventor:

Eben W. Keyes

United States Patent Office.

EBEN W. KEYES, OF BOSTON, MASSACHUSETTS.

Letters Patent No. 65,816, dated June 18, 1867.

PARLOR TEN-PIN ALLEY.

The Schedule referred to in these Letters Patent and making part of the same.

TO ALL WHOM IT MAY CONCERN:

Be it known that I, EBEN W. KEYES, of Boston, in the county of Suffolk, and State of Massachusetts, have invented a new and improved Parlor Alley; and I do hereby declare that the following is a full and exact description thereof, reference being had to the accompanying drawings, and to the letters of reference marked thereon.

The nature of my invention consists in so arranging a parlor alley that it can be played alternately from either end, the buffers or end guards being so arranged that they may be folded down.

To enable others skilled in the art to make and use my invention, I will proceed to describe its construction and use.

Drawings.

Figure 1 is an isometric perspective view.

Figure 2 is a longitudinal section; and

Figure 3 is a plan of my improved parlor alley.

To construct my parlor alley I proceed as follows: I form a case of any suitable material by uniting with the base-piece A the side-pieces C C' and the end pieces E E', as shown in the drawings. Within this case the alley B is fastened. This alley is narrower and shorter than the inside of the case, so as to leave room between the sides and ends of the alley and case for the balls and pins. The ends of the alley B are rabbeted, as shown in fig. 2, so that the padded ends or buffers D D' may be folded or laid down even with the upper surface of the alley B. The insides of the buffers D D' are padded so as to check the rebound of the balls or pins. In the drawings these buffers are represented as being connected with the ends of the case by means of hinges, but these hinges might be dispensed with and pins or hooks substituted.

To play with my improved alley, the alley is placed upon a table, and the players seat themselves at either end, each being provided with a set of ball's and pins. One player, for instance, the one at D, adjusts the buffer D at his end of the alley and sets up the pins for his adversary; the player at D' lowers the buffer D', and rolls the balls until the whole set of pins at D are knocked down, or until all the balls are rolled; then the entire proceeding is reversed and the player at D rolls.

Having thus described my invention, I will now proceed to set forth my claim.

What I claim as my invention, and desire to secure by Letters Patent of the United States, is—

A parlor alley made with movable or folding buffers D D', substantially as described and for the purpose set forth.

EBEN W. KEYES.
